Primary Examiner — Robert M Spear*Assistant Examiner* — Ryan Harvey*(74) Attorney, Agent, or Firm* — Levenfeld Pearlstein, LLC(57) **CLAIM**

What is claimed is the ornamental design for an exercise weight, as shown and described.

DESCRIPTION

FIG. 1 depicts the left side view of the exercise weight, the right side view being identical thereto;

FIG. 2 depicts the front view of the exercise weight, the back view being identical thereto;

FIG. 3 depicts the top view of the exercise weight, the bottom view being identical thereto; and,

FIG. 4 is a perspective view of the weight.

In the drawings, the broken lines depict indicia that form no part of the claim.
